UNITED STATES PATENT OFFICE.

CHARLES A. KIMPTON, OF MALDEN, ASSIGNOR OF THREE-FOURTHS TO
JOSIAH C. BENNETT AND FREDERICK L. WHITE, BOTH OF LYNN,
MASSACHUSETTS.

CAR HEATING AND VENTILATING APPARATUS.

SPECIFICATION forming part of Letters Patent No. 419,456, dated January 14, 1890.

Application filed March 2, 1889. Serial No. 301,748. (No model.)

To all whom it may concern:

Be it known that I, CHARLES A. KIMPTON, of Malden, in the county of Middlesex and State of Massachusetts, have invented certain new and useful Improvements in Car Heating and Ventilating Apparatus, of which the following is a specification.

It is the object of my invention to provide improved means whereby fresh air, either heated or at its natural temperature, may be supplied to the interior of a car or train of cars for the purpose of ventilating, or both warming and ventilating, the same.

My invention consists as a whole in a car heating and ventilating apparatus embracing a car provided with two pipes or two sets or series of pipes for receiving air from the exterior of the car, a heating device with which one of said pipes or series of pipes communicate for heating the air passing therethrough, said other pipe or series of pipes connecting or communicating with the pipe or pipes containing heated air, and valves for controlling the amount of air passing or that may be passed through said pipes.

Of the accompanying drawings, forming a part of this specification, Figure 1 represents a side elevation (parts being represented as broken away and parts shown in section) of a car equipped with my invention. Fig. 2 represents a partial longitudinal section of a passenger-car fitted with pipes to receive air from the car shown in Fig. 1. Fig. 3 represents a section on line $x-x$, Fig. 2. Fig. 4 represents a partial longitudinal section of a passenger-car, showing a modification of the arrangement of the air-circulating pipes. Fig. 5 represents a section on line $x'-x'$, Fig. 4.

a designates a car, through which, near the roof, pass two pipes b c , the former communicating with the heater and steam-generator d through the medium of a connecting-pipe e , and with the pipe c through the medium of pipes f f' and g , which are connected with the blower h .

1 and 2 designate valves in pipe b .

4 and 5 designate valves in pipe c .

3 and 6 designate valves in pipe f , and 7 50 designates a valve in a pipe g' which connects pipes f and f' with pipe c .

When the car is moved in the direction of the arrow marked on the drawings, and it is desired to convey warm or heated air into a 55 car or cars in the rear, valve 1 will be opened and valve 2 closed, so that the air entering pipe b will pass through connecting-pipe e to the heater d , and through the coils i in the heater, where it will be heated. Valves 3 and 60 5 will be opened and valves 7, 4, and 6 closed, so that the air from the heater may be drawn by the blower h through pipes f f' , and forced through pipe g out through the rear end of pipe c . Should it be desired to shut 65 off the warm or heated air and convey cold or cool air only to the cars in the rear, valve 3 will be closed and valve 7 opened, when the air will be drawn by the blower through pipes c and f' and forced out as before. 70

When the car is moved in a direction opposite to that indicated by the arrow, and it is desired to convey air through and discharge it from the pipes in a direction opposite to that before described, if warm or heated air 75 only is to be used, valves 1, 5, 6, and 7 will be closed and valves 2, 3, and 4 will be opened, when the blower h will draw air in through pipe b , connecting-pipe e , the coil i in the heater, and through pipes f f' , and force it 80 out through pipes g and c . Should it be desired to shut off the warm or heated air under the last-mentioned conditions and employ cold or cool air alone, valve 3 will be closed and valve 6 opened, when the air will be 85 drawn in through pipes c , f , and f' , passing valve 6 and be forced out through pipes g and c , as before.

If it is desired to regulate the temperature of the air supplied to the cars by mingling 90 cool air with the air which passes through the heater when the train is moving in the direction indicated by the arrow, the valve 7 is opened to any desired extent, the valves 4 and 6 remaining closed, as before. A supply 95 of cool air from the pipe c is thus admitted to the pipe f' and passes with the warm air from the heater through the blower to the

cars. When the train is moving in the opposite direction, the same result may be produced by closing the valve 7 and opening the valve 6. It will be seen, therefore, that fresh air 5 may be supplied to the cars either at its natural temperature or raised to any desired higher temperature within the capacity of the heater, so that the cars are thoroughly ventilated and may be easily kept at the desired 10 temperature. The air thus supplied may be distributed through the passenger-cars by main pipes p , extending lengthwise of the cars and communicating through suitable couplings c' with the pipe c , said pipes having 15 suitable outlets or branches p' , through which the air is discharged at numerous points into the car. (See Figs. 2 and 3.)

Each of the branches p' is preferably provided with a valve v , whereby the air may be shut off, if desired, so that each passenger 20 may control the admission of air to his or her immediate vicinity.

If preferred, the longitudinal pipe p may be arranged on the floor of the car with its branches p' under the seats, as shown in Figs. 25 4 and 5, in which case two pipes p should be employed—one at each side of the aisle.

Provision is made in the heater d for generating steam, which is conveyed through the medium of pipe j to the engine k , from which, 30 through the medium of belts and pulley the blower h is operated, as may also be a dynamo-electric machine l , by which electricity may be generated for the purpose of lighting the 35 cars.

It is to be observed that the valves of the several pipes may be so adjusted as that the heated and cool air may be forced through the pipes at the same time, and in any desired 40 proportion with respect to each other.

The contrivance is simple in organization and may be constructed and operated at comparatively low cost.

It is obvious that changes may be made in 45 the form and arrangement of parts without departing from the nature or spirit of the invention.

I claim—

1. In a car heating and ventilating apparatus, the combination of a car, a heater, and a blower therein, a system of pipes or conduits whereby external air is conducted through the heater to the blower and from the latter to a succeeding car, said system including a 55 pipe to receive external air and conduct it to the heater, and a pipe c , which extends through the car and is adapted to be opened to the external air at either end of the car, so as to introduce cold air or air at its natural 60 temperature from either end of the car into the heated air in said pipes, and means for controlling or regulating the quantity of cold air thus admitted, as set forth.

2. In a car heating and ventilating apparatus, the combination of a car, a heating apparatus, and a blower or air-forcing apparatus in said car, means for admitting fresh ex-

ternal air to the heater, a conduit for the heated air from the heater to the blower, an air-pipe extending into the car from opposite ends thereof, a connection between said pipe and the blower, valves in said pipe at opposite sides of said connection, whereby either end of said pipe may be made the receiving end and the other the discharging end, and independent valved connections between said pipe and the hot-air conduit, at opposite sides of the said blower-connection, whereby either end of the air-pipe may be connected with said conduit to supply fresh air thereto, as set forth.

3. In a car heating and ventilating apparatus, the combination, substantially as hereinbefore set forth, of a car, a heater, and an air-forcing apparatus or blower therein, cold-air-supply conduits presenting air-receiving ends in opposite directions and communicating with the heater, whereby outside air may be supplied to the heater from either end of the car, a hot-air conduit, as $f'f$, between the heater and blower, whereby the air supplied to the heater by the cold-air conduits is conducted after it is heated to the blower, a pipe c , extending through the car and having coupling members at its ends, either of which is adapted to be connected with a coupling-pipe section communicating with another car, the forward end of said pipe receiving outside air, while its rear end discharges warm air, a connection, as pipe g , between the blower and the discharge end of pipe c , whereby the air is conducted from the blower to said discharge end, valved connections, as pipes $g'g''$, connecting the pipe c at opposite sides of the pipe g with the hot-air conduit, and valves 4 5 in the pipe c , whereby either of said valved connections may be put in communication with the hot-air conduit to admit cold air from either end of the pipe c to said conduit, as set forth.

4. In a car heating and ventilating apparatus, the combination of a car, a heater, and a blower therein, a pipe b , presenting receiving ends in opposite directions to the external air, whereby the motion of the car in either direction causes the entrance of cold air through said pipe, a coil or conduit in the heater connected with the pipe b , valves 1 2 in said pipe b at opposite sides of the connection thereof with said coil, a hot-air pipe or conduit, whereby heated air is conducted from the heater to the blower, an air-pipe c , extending through the car and presenting its ends in opposite directions to the external air, one of said ends constituting an air-receiving and the other an air-discharging end, a pipe connecting the receiving end of the pipe c with the hot-air conduit within the car, another pipe connecting the blower with the discharge end of the pipe c , and valves whereby the passage of cold air from the pipe c into the hot-air conduit may be controlled, as set forth.

5. The combination of a car, a heater and a blower therein, a pipe b , presenting air-re-

ceiving ends to the external air in opposite directions, a coil or conduit in the heater connected with the pipe *b*, the valves 1 2 in said pipe, the pipes *f f'*, whereby hot air is conducted from the heater to the blower, the cold-air-supply pipe *c*, extending through the car and having its ends outside the car, the pipe *g*, connecting the blower with the pipe *c*, the pipes *g' g''*, connecting the pipe *c* with the receiving side of the blower at opposite sides of the pipe *g*, and the valves 4 5 6 7, whereby the passage of air through the pipes *c*, *g'*, and *g''* may be controlled, as set forth.

6. A passenger-car having a system of air-distributing pipes, including a longitudinal pipe *p*, extended through the ends of the car, combined with a heating-car, a heater and a blower therein, a system of pipes or conduits whereby external air is conducted through

the heater to the blower and from the latter 20 through the rear end of the heating-car, said system including a pipe *c*, which extends through the heating-car and is adapted to be opened to the external air at either end thereof, so as to introduce air at its natural temperature from either end of the car into the heated air in said pipes, and means for detachably connecting the rear end of the pipe *c* of the heating-car to the forward end of the pipe *p* of the passenger-car, as set forth. 25 30

In testimony whereof I have signed my name to this specification, in the presence of two subscribing witnesses, this 28th day of February, A. D. 1889.

CHARLES A. KIMPTON.
